UNITED STATES PATENT OFFICE

164,884

TOY SIMULATING A CANOE WITH PADDLERS

Harry Sebel, Finchley, London, England

Application March 7, 1950, Serial No. 8,387

Term of patent 14 years

(Cl. D34—15)

To all whom it may concern:

Be it known that I, Harry Sebel, a subject of the King of Great Britain, residing at 13, Kinloss Gardens, Finchley, London, N. 3, England, have invented a new, original, and ornamental Design for Toy Simulating a Canoe With Paddlers, of which the following is a specification, reference being had to the accompanying drawings, forming part thereof.

Fig. 1 is a perspective view of a toy simulating a canoe with paddlers, showing my new design;

Fig. 2 is a bottom plan view thereof;

Fig. 3 is an elevational view of the side opposite that shown in Fig. 1; and

Fig. 4 is a top plan view thereof.

I claim:

The ornamental design for a toy simulating a canoe with paddlers, as shown.

HARRY SEBEL.
